UNITED STATES PATENT OFFICE.

FREDERICK C. BILLINGS, OF MILWAUKEE, WISCONSIN.

PRINTING-PRESS FOR MUSIC-ROLLS.

1,263,023.

Specification of Letters Patent. Patented Apr. 16, 1918.

Application filed March 24, 1917. Serial No. 157,121.

To all whom it may concern:

Be it known that I, FREDERICK C. BILLINGS, a citizen of the United States, residing at Milwaukee, county of Milwaukee, and 5 State of Wisconsin, have invented new and useful Improvements in Printing-Presses for Music-Rolls, of which the following is a specification.

My invention relates to improvements in 10 printing presses for music rolls.

The object of my invention is to provide means for printing music upon the border portions of perforate music rolls embodying an invention disclosed in U. S. Letters Patent 15 #1,194,811, dated August 15, 1916.

My invention contemplates a structure having a rotary turret and means for intermittently reciprocating the turret along a vertical plane, the turret being rotated 20 step by step and serving as a press in the intervals between the step by step movements. The turret is provided with sets or rows of type blocks or plates, each provided with wood cuts, electrotypes or type adapted 25 to print a fragment of a musical staff similar to those disclosed in said former patent.

I propose by reciprocating the turret in a vertical plane to bring a series of printing plates into pressure contact with a music 30 sheet or portion of a music roll disposed upon a table underneath the turret, whereby a series of staff fragments may be simultaneously printed upon said strip or music roll. I then propose to lift the turret, rotate it one step to bring another set of plates into printing position, and in the mean time advance the strip or music roll to remove the printing portion from the table and expose an unprinted portion thereof for the 35 next printing operation, the turret being then depressed to bring the second set of plates into contact with the strip. By providing a turret having a sufficient number of plates mounted thereon, it is possible for 40 me to provide plates representing an entire musical production and mount them all upon the turret preparatory to the printing operations. Then by advancing the music roll strip step by step and rotating the 45 turret step by step in the intervals between printing operations, I am enabled to present 50

all of the sets of plates successively in position for printing.

In the drawings:

Figure 1 is a side elevation of a printing 55 press embodying my invention.

Fig. 2 is an end elevation of the same.

Fig. 3 is a sectional view on line 3—3 of Fig. 1.

Fig. 4 is a sectional view on line 4—4 of 60 Fig. 2.

Fig. 5 is a sectional view on line 5—5 of Fig. 2.

Fig. 6 is a fragmentary sectional view showing means for doweling the turret. 65

1 is a table along which a music roll strip 2 may be fed. For the purpose of the present invention, it may be assumed that the strip will be advanced manually along the table so as to expose successive portions 70 thereof upon the table for the printing operations. The frame 3 of the press is formed to provide a feedway 4 through which the strip may be passed along the table, and above that portion of the strip designed to 75 receive the printing operations, the frame is provided at each end with a slide 5 mounted to reciprocate vertically in suitable guides formed in the stationary portion of the frame. Each slide is actuated from gear 80 wheel 7, shaft 8, crank disk 9, crank pin 10, and connecting rod 11, and in Fig. 2 the slide is shown in raised position.

A turret 15 is journaled in the slides, its central shaft 16 projecting through the vertical end bars of the slides and serving as a means for connecting the lower ends of the connecting rods 11. The turret is provided with a series of longitudinally extending rows of type plates 20, preferably removably secured to the turret and having their outer faces adapted to receive printing members or type 21.

It will be observed, in Fig. 2, that one of the rows of plates is horizontally disposed 95 along the lower side of the turret, whereby a downward movement of the slides 5 and the turret will bring all the plates in this row into contact with the paper strip 2. This contact will occur during the final 100 downward movement of the slides and the turret, as the crank pin completes a one-

half turn from its position as illustrated in Fig. 2.

It will be observed that the turret 15 is provided, preferably on each end, with an annular row of pins or studs 25, projecting longitudinally from the heads or ends of the turret. One of these pins is shown in Fig. 2 in engagement with a notch formed in the lower end of a pawl 26. The lower end of 10 this pawl 26 has a projecting lip 27 constituting an extension of the outer wall of the notch or socket 29 in which one of the pins 25 is engaged. When the turret moves downwardly, the next succeeding pin 25 bears 15 upon the inner edge of the pawl 26 and pushes said pawl downwardly, causing it to swing upon its pivot shaft 30. Preparatory to this movement, the engaged pin 25 will have moved downwardly out of the socket 29 in 20 the lower end of the pawl 26, thereby permitting the pawl to swing outwardly under the pressure exerted by the next stud or pin 25 until such stud or pin has moved downwardly far enough to allow the shoulder 31 25 on the pawl to clear this stud or pin, whereupon the pawl will again swing inwardly until its inward movement is arrested by lip 27 striking said second stud 25. It is not material to the invention whether the pawl 30 is actuated by gravity or whether it is spring actuated. It is merely necessary that it should have a tendency to swing inwardly to its position as illustrated in Fig. 2, when not pressed outwardly by a downwardly 35 moving pin or stud 25.

With the construction illustrated, the studs or pins 25 are spaced apart in correspondence with the spacing of the rows of plates 20 and also in correspondence with 40 the vertical movement of the turret, in such a manner that when the turret moves to printing position, the pin shown as engaged in Fig. 2, will not only be withdrawn from the pawl 26, but the second pin or stud 25 45 will have moved downwardly to a point slightly below the level of the engaged pin 25, in Fig. 2, thus permitting the latch shoulder 31 to swing inwardly across the said pin, the notch 29 of the latch being directly above the pin in a position to receive 50 the pin as soon as the upward movement of the turret commences.

During the upward movement of the turret, the latch 26 will actuate it, rotating the 55 turret one step, whereupon said second pin 25 will, at the completion of the movement, occupy the identical position of the first pin 25 as illustrated in Fig. 2, and inasmuch as these pins are spaced in correspondence with 60 the spacing of the plates 20, it is obvious that a second set of plates will then be swung into horizontal position at the bottom of the turret. The music strip or sheet will be advanced, while the turret is raised, to 65 expose an unprinted portion on the table

and the printing operation may then be repeated with the second set of plates, after which the turret again moves upwardly, pawl 26 advances it another step, thereby bringing the third set of plates into position 70 for printing, and the music strip having been again advanced, a third printing operation may be performed.

During the downward movements of the turret, the plates of that set which are next 75 to swing to operative position, are caused to travel over an inking roller 40, the ends of which are journaled in hangers 41. These hangers are drawn resiliently in the direction of the turret by springs 42 and 80 the roller 40 and hangers are pushed outwardly by the plates, the latter being obliquely positioned with reference to the vertical plane in which they move. After the relative traverse of roller 40 across the 85 row of plates has been completed, the roller is pushed still farther outwardly by brackets 44 connected with the slide 5, and during the completion of the downward stroke of the turret, this roller 40 is held against a 90 loose pulleys 43 on the ends of roller shaft 39.

When the turret moves upwardly, roller 95 40 swings inwardly to position for supplying ink to the next set of printing plates, which are presented to the roller by the action of the pawls 26.

Ink is supplied to the carrying roller 46 100 from a reservoir 47 in which a feeding roller 50 operates. Any suitable means for feeding the ink may be employed, but I preferably provide a conveying roller 51, journaled in swinging arms 52 and alternately 105 moved into contact with the rollers 50 and 46, remaining in contact with each for a suitable interval to receive or deliver the ink. Roller 50 is rotated at intervals, motion being transmitted to it from a cam projection 55 on disk 9, through elbow crank 56, link 57, elbow crank 58, pawl 59 and ratchet wheel 60, the latter being fast on the shaft of roller 50. Roller 51 may be normally held in contact with roller 46 by 110 gravity, and may be swung into contact with roller 50 by rods 66 mounted to slide in guide ways formed in frame member 67 and each having its inner end 68 in the path of one of the hangers 41, its other end being 115 adapted to press against a spring 69 connected with arm 52. When the hangers 41 swing outwardly as above explained, the conveying roller 51 is resiliently pressed against the ink feeding roller 46 by pressure 120 exerted through the rods 66 and springs 69. Frame member 67 is adjustably mounted on the main frame, adjusting screws 64, 65 being employed for this purpose.

Link 57 is adjustable along the connected 125

arms of the elbow cranks 56 and 58, said arms being preferably provided with slots 70 and 71 respectively, through which the connecting pins or bolts extend. 75 is a distributing roller, bearing upon roller 46. Being of smaller diameter and idly driven by frictional contact, it serves to spread the ink upon the surface of roller 46 with substantial uniformity. It is oscillated longitudinally by a cam 76 to facilitate the spreading operation.

The machine above described may be operated manually by means of a crank 80 (Fig. 1) mounted on shaft 8, or by any suitable motor. Motion may be transmitted from shaft 8 to the ink carrying roller 46 through the belt 81 and shaft 82, roller 46 being mounted on said shaft. The belt runs over pulleys 83 fast on shaft 8 and 82 respectively.

By referring to Figs. 1 and 3, it will be observed that each of the plates 20 is mounted to slide longitudinally along its retainer bar 85, the retainers 85 mounted on the peripheral wall of the turret. Each of these retainers 85 is provided with a longitudinal slot 86 and the type plates are provided with connecting screws or bolts 87 (Fig. 3) projecting through said slits, whereby the plates 20 may be clamped to the retainer 85 in any desired position, preparatory to securing the retainer in position on the turret. By making the retainers demountable, the type plates may be easily replaced or shifted.

This is an important feature of my invention, since it enables me to print the music in proper relation to the perforations in a perforate music roll designed for use in connection with a piano player as disclosed in said prior patent. In the drawings, I have shown the plates equally spaced from each other, but in practice this uniform spacing will seldom occur, the length of the spaces being varied to suit the requirements of the music and of the perforations. The turret heads are provided with sockets 90 in which a spring actuated locking pin 91, carried by each of the slides, is adapted to engage. The locking pins 91 have tapered extremities and the socket walls are correspondingly tapered, whereby the pin may be forced out of any given socket when the turret is rotated. The sockets are so located that when the pin is in engagement with one of them, a set of printing plates will be in printing position, *i. e.*, horizontally disposed at the bottom of the turret. These locking pins, one at each end of the turret, hold the turret in position against accidental displacement during printing operations.

I claim—

1. A printing machine for printing music roll strips adapted for printing fragments of a musical staff upon a music roll strip, including the combination of an elongated

table to receive the strip and over which the strip may be advanced longitudinally step by step, a vertically movable carrier, having its axis disposed longitudinally of the strip, a longitudinal row of type carrying plates 70 supported by the carrier, and means for reciprocating the carrier with its axis parallel to the table to move the plates into and out of contact with the strip.

2. A printing machine for printing music 75 roll strips adapted for printing fragments of a musical staff upon a music roll strip, including the combination of a table over which the strip may be longitudinally fed, a vertically movable carrier, a turret rotatively mounted on the carrier with its axis extending longitudinally of the strip and provided with longitudinal rows of type carrying plates, means for reciprocating the carrier to bring the lower row of plates into 80 contact with the strip at successive points along the length thereof, and means for rotating the turret when the carrier is raised, to present successive rows of plates in printing 85 position.

3. A printing machine for printing music roll strips, including the combination with a reciprocatory carrier, of a turret rotatively mounted on the carrier and provided with type carrying plates, means for reciprocating the carrier to bring the lower row 90 of plates into and out of printing position, means for rotating the turret step by step to present different plates in printing position, and means for feeding music roll strips 100 longitudinally of the turret and supporting portions thereof in the path of a row of plates.

4. A printing machine for printing music roll strips, including the combination of a 105 table adapted to receive a sheet to be printed, a reciprocatory carrier, having its axis disposed longitudinally of the table, a turret rotatively mounted on the carrier and provided with type carrying plates arranged in 110 rows and adapted for printing successive portions of a column of characters, means for adjusting the plates along the axis of the turret, and means for reciprocating the carrier to bring different plates into printing 115 relation to a music roll strip which is being advanced upon the table longitudinally of the turret.

5. A printing machine for printing music roll strips, including the combination of a 120 support for the material to be printed upon, a reciprocatory carrier, having end standards spaced apart to allow a music roll strip to pass between them, means for simultaneously raising and lowering both ends of the 125 carrier, a turret rotatively mounted in the carrier and provided with longitudinal rows of type carrying plates, means for reciprocating the carrier to bring all the plates of one row of plates simultaneously into and 130

out of contact with the material, means for automatically rotating the turret when retracted from the material to substitute one set of plates for another in printing position.

6. A printing machine for printing music roll strips including the combination of a support for the material to be printed upon, a reciprocatory carrier having end standards 10 between which the strip may be passed, and provided with longitudinal rows of type carrying plates, positioned longitudinally of the path of a strip fed over the table between the respective sets of end standards, 15 means for reciprocating the carrier to bring one row of plates into and out of contact with the strips, means for automatically rotating the turret when retracted from the material to substitute one set of plates for 20 another in printing position, together with means for adjusting the plates of a set in various spaced relations to each other.

7. In a printing press, the combination with a drum shaped turret, of sets of longitudinally extending slotted retaining bar plates on each retainer bar in a longitudinal row, means for adjusting the plates longitudinally of the turret in various spaced relations on each other, clamping screws 30 passing through the retainer bar slots and securing the plates thereto, and end fastening connecting the retainer bars with the plates.

8. In a printing machine for printing music roll strips, the combination with a reciprocatory carrier, a rotary turret supported thereby, a series of sets of printing plates mounted upon the turret, a stationary support for the carrier, and an actuating member mounted thereon in a position to engage and rotate the turret a distance equal to the distance between two adjacent sets of plates, during each retractive movement of the carrier.

45 9. In a printing machine, for printing music roll strips, the combination with a

table, a set of supporting end standards provided with a passage through which the music roll strip may be passed along the table, a set of slides mounted on the standards, a rotary turret supported thereby with its axis extending longitudinally of the strip feed way, and an actuating member mounted on one of the standards in a position to engage and rotate the turret a distance equal 50 to the distance between two adjacent sets of plates, during each retractive movement of the carrier, and means for supplying ink to printing devices on the plates during said retractive movements.

60 10. A printing machine for printing music roll strips including the combination with a reciprocatory carrier, of a turret rotatively mounted on the carrier and provided with type carrying plates, means for reciprocating the carrier to bring all of the plates in the lower row of plates simultaneously into and out of printing position, means for rotating the turret step by step to present different plates in printing position, means for resiliently holding the turret in printing position during the intervals between step by step rotative movements, and means for supporting a music roll strip longitudinally of the turret whereby fragments of the music 70 75 may be printed upon the strip in column or form.

11. In a printing machine for printing music roll strips, the combination of a turret provided with a series of disposed longitudinally extending removable plate supporting bars, each longitudinally slotted, a set of printing plates mounted on each bar and clamping set screws each extending through a slot and engaging one of the 80 85 plates.

In testimony whereof I affix my signature in the presence of two witnesses.
